[57] **CLAIM**

The ornamental design for multi-faced doll, as shown and described.

DESCRIPTION

FIG. 1 is a perspective view of the multi-faced doll showing my new design;

FIG. 2 is a side elevational view thereof;

FIG. 3 is a partially broken-away view of the doll of FIG. 2;

FIG. 4 is a top plan view thereof; and

FIG. 5 is a bottom plan view thereof.

The undisclosed second and third side of the upper and lower portion are mirror images of those shown. The facial features are shown in broken lines for illustrative purposes only.

Fig. 1

Fig. 5
